UNITED STATES PATENT OFFICE.

ALBERT C. JACKSON, OF DAYTON, OHIO.

DISPLAY TRAY.

Application filed March 14, 1924. Serial No. 699,296.

This invention relates to new and useful improvements in display trays, and more particularly to trays which are adapted to display circulars, pamphlets and other literature.

It is one of the principal objects of my invention to provide an ornamental, compact and easily assembled display tray unit for use in banks, trust companies and like institutions for displaying circulars, pamphlets and other literature. Starting with a single tray section, others may be added as desired to form a compact and attractive unit.

It is another object of my invention to provide simple and effective means for detachably securing the tray sections together.

Still another object of the invention is to provide in each tray section, partitions which may be easily adjusted in different positions to provide literature-receiving spaces of various widths, and which may be firmly held and braced in the positions to which they have been moved.

Another object of my invention is to provide means on the back of a tray to easily receive, and firmly support, an attractive sign calling attention to the contents of the tray or trays.

And still another object of the invention is to provide a retaining member which is pivotally secured to the end walls of the tray to assist in holding the pamphlets therein.

Other important and incidental objects will be brought out in the following specification, and particularly set forth in the subjoined claims.

In the accompanying drawings, Figure 1 is a front elevational view of the vertical type of tray. Figure 2 is a plan view of one of the horizontal trays. Figure 3 is a cross sectional view taken on the line 3-3 of Figure 2. Figure 4 is a cross sectional view taken on the line 4-4 of Figure 1. Figure 5 is a perspective view of one of the adjustable partitions for the horizontal type of tray. Figure 6 is a perspective view of one of the adjustable partitions for the vertical type of tray. Figure 7 is a front view of a tray supporting post, showing the dowel pin and hole arrangement in its base or foot portion for connecting the tray sections together. Figure 8 is a sectional view taken through the base of said post on the line 8-8 of Figure 7. Figure 9 is an end view

of the vertical type of tray. Figure 10 is an end view of two horizontal trays connected together by the dowel pins. And Figure 11 is a perspective view of one corner of the frame of a horizontal tray, without the bottom, showing the means for supporting the latter in the tray and the means for securing the front and end members of the tray together.

Referring to the accompanying drawings for a detailed description of the invention, the numeral 1 designates a front horizontal-tray member which is preferably cast from bronze and flanged along its top edge. Projecting inwardly from each end of the front member 1, is an ear 2 to which there is secured, by a screw 3, the inner front part of an end member 4 that is also preferably cast from bronze and flanged along its top edge. (See Figures 2, 3 and 11.) While I employ the above means for securing the front and end members of a horizontal tray together, any other suitable means may be employed for this purpose if desired.

Formed on each end of the end members 4, 4, and on the middle part of the member 1, is an ornamental post 5. These posts have wide flanged tops, the ones on the front posts of the end members projecting over the flanged top edge of the front member 1. These posts 5 also have wide bases or feet 6.

Projecting inwardly from the lower portion of the front member 1, are two rows of lugs 8, the latter being alternately arranged to receive between them the front end of a tray bottom 9 which is preferably constructed of enameled steel. Referring to Figure 3, this tray bottom is bent upwardly at its rear end to form a rear wall 10 for the tray of substantially the same height as the front member 1, and then forwardly to form a flange 11 of the same approximate width as the inner flange on the top edge of said front member. The metal is then turned back upon itself, and thence downwardly to a point where it is bent inwardly to form a horizontal flange 12 for support upon the inwardly projecting parts of the bases 6 of the rear posts 5.

To the tops of the rear posts 5, which are taller than the front ones, the flanged top edges of the end members 4, 4, incline upwardly. Projecting inwardly from these end members at points to support the tray bottom 9 at substantially the same inclination as the tops of the end members, are

lug 13. Formed on the rear posts 5 are ears 14 through which screws 15 are passed into the downwardly projecting rear part of the tray bottom 9 to firmly secure the latter to said posts. The middle front post 5 has an ear 16 formed on its base that projects under, and is secured to, the front middle portion of the tray bottom 9.

Suitably secured to the bottom of the horizontal portion 12 of the downwardly extending part of the tray bottom, is the flanged lower end of an upwardly projecting strip 17 which is preferably constructed of enameled steel. This strip is so secured to the flanged part 12 of the tray bottom 9, that its upright part will be held a sufficient distance from the rear portion of the tray bottom to form therewith a pocket to receive a card 18 to display on its face suitable wording calling attention to the contents of the tray. (See Figure 3.)

The horizontal tray is divided into literature-receiving spaces of the desired width, by partition members 19, each one of which is preferably constructed of bronze. The front end of each partition member has the same inclination as the front member 1 of the tray, and its rear end has the same inclination as the rear wall 10 of the latter, so that the partition member may rest upon the tray bottom 9 with its ends in relatively snug engagement with the front and rear walls of the tray, and yet free to be moved over the bottom surface of the tray into an adjusted position.

Formed on the lower part of the partition members 19, near each end thereof, are oppositely projecting feet 20, to the bottom portions of each pair of which there is secured a felt or similar strip 21 to yieldingly rest upon the surface of the tray bottom 9. (See Figure 5.) Each partition member 19 also has a flanged top 22 which does not extend quite to the ends of said member to leave spaces thereon which will slide freely beneath the flanges on the front and rear walls of the tray. When a partition member has been moved to an adjusted position in the tray, the feet 20 of the partition member will co-operate with the flanges on the tops of the tray walls to firmly hold and brace it in the position to which it has been moved.

For the purpose of connecting two or more tray sections in longitudinal alignment, or one behind the other, any suitable means such as the following may be employed. Referring to Figures 7 and 8, there projects rearwardly from the base 6 of each rear post 5 of a tray section, a dowel pin 23 for entrance into a hole 24 formed in the base of the front post 5 of the tray section behind it. And projecting forwardly from the base of each front post 5 of the latter tray section, is a dowel pin 23 for in-

sertion in a hole 24 formed alongside the inner end of the dowel pin in the base of each rear post of the front tray section. It is an easy matter to insert these dowel pins in the holes in the tray posts, to neatly and firmly connect the tray sections into a unit as shown in Figure 10, with the card 18 supported in the pocket formed on the rear tray section.

In Figures 1, 4 and 9 I have shown an upright tray section for support upon narrow ledges or other places to display circulars, literature and other advertising media in a vertical manner. In this type of tray, the outer edges of the end walls 4, 4, incline upwardly almost perpendicularly to the tops of very tall rear posts 5 formed on their rear ends. The tray bottom 9 at a short distance from the front wall of the tray, inclines sharply upwardly to a point to bring its flange 11 just below the tops of the rear posts 5, and then extends rearwardly and downwardly a sufficient distance to bring its lower flange 12 upon the post bases for support thereby. (See Figure 4.)

Referring to Figure 6, the numeral 25 designates one of the partition members that are employed in the upright display tray. Each one of these members is preferably cast with a square base, from which it extends upwardly at substantially the same inclination as the outer edge portions of the end walls of the tray. Each partition member has a flanged top 26 that does not quite extend to its ends to leave spaces thereon for entrance below the flanges on the front and rear walls of the tray. Formed on the bottom part of each partition member 25, and along its rear end, are pairs of outwardly projecting lugs 27 to the bottom portions of which are secured felt or like pads 28. Each partition member 25, as well as each partition member 19, is notched at its lower front end to clear any of the lugs 8 that may project into its path of movement. The partition members 25, constructed as above described, are as free to be moved to desired positions, and to be as firmly braced and held there, as are the partition members 19. (See Figures 1 and 4.)

Secured to the downwardly projecting part of the upright tray bottom 9, near the upper end thereof, is a flanged strip 29 which, like the strip 17, is held a sufficient distance away from the back part of the tray bottom to form a pocket to receive one of the sign cards 18. (See Figures 1 and 4.)

Preferably molded at opposite points near the tops of the end members 4, 4 in both the horizontal and upright trays, are bosses 30 containing holes to receive the outer ends of an arched retaining rod 31 to hold the circulars or other advertising media firmly in the tray. The ends of the rod are free to turn in these bosses so that the portion of it

which engages the pamphlets in the tray, may be raised to facilitate their insertion and withdrawal. (See Figures 1, 2 and 4.)

Having described my invention, I claim:

5 1. In a display tray, a bottom, a front and a rear wall, a flange formed on the top of the front and the rear wall, a partition member longitudinally movable over the bottom of said tray, and cut away at its upper ends to engage under said flanges, and bracing projections on the bottom of said partition member.

10 2. In a display tray, a bottom, a front and a rear wall, a flange formed on the top of the front and the rear wall, a partition member longitudinally shiftable over the bottom of said tray, a flange formed on the top of said partition member that does not quite extend to the ends thereof, to leave 15 spaces for entrance beneath the flanges on the front and rear walls of the tray, and

bracing feet formed on the bottom of said partition member.

3. A display tray having a front wall, a top flange formed thereon, end walls, a bottom member secured between said front wall and end walls, said bottom member being turned upwardly at its rear end, and then forwardly to form a flange, and a partition member whose ends project under said flange 25 and the flange on the front wall, for movement over the bottom of the tray.

4. A display tray having a bottom, a front wall, a rear wall, and end walls, partition members between the front and rear walls, 30 and a bail shaped retaining rod crossing said partition members and whose ends are pivotally secured to the end walls for the purpose specified.

In testimony whereof I have hereunto set 40 my hand this 12th day of March, 1924.

ALBERT C. JACKSON.
